UNITED STATES PATENT OFFICE.

FORTUNATO SORDILLO, OF DORCHESTER, MASSACHUSETTS.

MUSIC STAND.

Application filed February 23, 1923. Serial No. 620,645.

To all whom it may concern:

Be it known that I, FORTUNATO SORDILLO, a citizen of the United States, residing in Dorchester, in the county of Suffolk and State of Massachusetts, have invented an Improvement in Music Stands, of which the following is a specification.

This invention relates to collapsible music stands.

10 The usual collapsible music stand is provided with two or more members which are adapted to be separated or completely detached from each other and separately collapsed in order that the stand may be folded 15 completely.

With such a construction it is quite common to lose one of the detachable members, or the screw or other fastening means adapted to connect the two detachable members, 20 when the separable members of the stand are detached and consequently the stand is or may be rendered incapable of further use.

An object of this invention is to provide a collapsible music stand wherein all parts 25 thereof are secured permanently together and to so arrange the stand that the component members thereof may be collapsed or folded to occupy, in the folded condition, but a small volume.

30 A further object of this invention is to provide a music stand with a novel construction of rack which is adjustable to support note sheets of variable sizes.

A yet further object of the invention is 35 generally to improve the construction of music stands.

Fig. 1 is a front elevation of the stand embodying the invention.

Fig. 2 is a sectional detail illustrating the 40 manner of connecting the telescoping tubes of the supporting standard.

Fig. 3 is a front elevation of the music rack and illustrating various adjustments of the adjustable members comprising the 45 stand.

Fig. 4 is a detail similar to Fig. 3 illustrating the rack in position to be finally folded into its most compact form.

Fig. 5 is a section along line 5—5 of 50 Fig. 1.

Fig. 6 is a sectional detail of the supporting pedestal and illustrating the manner in which the pedestal is locked in expanded position.

55 Fig. 7 is a view illustrating the stand

with the component parts collapsed upon themselves and in readiness for the final folding operation.

Fig. 8 is a view of the completely folded and collapsed stand. 60

As here shown, the music stand embodying this invention includes the supporting standard having the telescoping tubes 10, 11, 12 and 13. The upper tube 13 is adapted to support the note sheet rack while the 65 lower standard 10 is adapted to be secured to and be supported by the base or pedestal. Said tubes 11 through 13 are all secured permanently together against detachment and are arranged in frictional engagement 70 with each other whereby the standard may be retained securely in any adjusted condition thereof.

As shown in Fig. 2, the frictional connection between the telescoping tubes includes the helical spring 14, which latter is disposed within the upper ends of the tubes. The upper ends of the tubes are reflexed inwardly or otherwise formed to provide an annular inturned lip 15 which is adapted 80 closely to conform to the next uppermost tube and retain said spring 14 therein against displacement as the tube 12 is drawn outwardly. Said tube 11 is also formed with an abutment disposed beneath said spring 14 85 whereby to hold said spring against any appreciable amount of axial downward movement within the tube. As here shown, said abutment comprises a ring 16 disposed with- 90 in said tube 11. Said ring may be secured to said tube in any suitable manner and, as here shown, is adapted to be soldered thereto, the solder being introduced into the peripheral channel 16^a of said tube 12 through an aperture 17 in the tube wall. Said spring 95 14 is adapted to be in substantially frictional engagement with the tube 12 so that said spring serves to grip said tube 12 snugly and thereby hold it securely in any adjusted position thereof, although said spring is not adapted to provide an undue restriction to 100 the manual collapsing operation of the standard.

Preferably, although not necessarily, said spring 14 is adapted to be somewhat compressed in the direction of its length in said outer tube 11 whereby the outer and inner tubes are or may be held against undue axial movement in relatively adjusted positions thereof. With this construction, it will be 110

apparent that all of the telescoping tubes of the standard are permanently secured and justably together.

The supporting pedestal includes the bracket 20 which is or may be secured about and to the lower end of the lowermost tube 10; and feet 21 are pivotally connected permanently to said bracket by suitable means as the rivets 22, whereby to form a tripodal support for the device. A second bracket 23 is slidably mounted on said lowermost tube 10 above said bracket 20; and links 24 are pivotally connected permanently with said bracket 23 and with said feet 21 intermediate the length thereof and in the same vertical plane with said feet. This arrangement is such that when said bracket 23 is moved along said tube 10 to the upper portion thereof, said feet 21 will be moved into a closed and approximately parallel relation with said tube, and as will also be the case with said links 24, whereby the pedestal and the lowermost tube 10 may be collapsed or folded into a compact formation as illustrated in Fig. 7.

Said bracket 23 is provided with means, permanently carried thereby, for connecting said bracket releasably with said tube 10 at the lower portion thereof as indicated in Fig. 1, so that the tripod may be supported securely in extended condition. Said connecting means may include the pin 25 which is received in a recess 26 in said bracket 23 and has an inner end portion which is adapted to register with an aperture 27 in the side wall of said tube 10 and move within said aperture under the pressure of its spring when in register therewith whereby to lock said bracket 23 releasably in position. Said pin 25 is or may be provided with an enlarged head 28, or other suitable manual engaging means, which is adapted to be grasped whereby the pin may be withdrawn from said hole 27 thereby to release the bracket 23 from its connection with said tube 10 and permit the tripod to be collapsed.

When the stand is being expanded for use, it is merely necessary to straighten out the feet 21 and said pin 25 will automatically be moved into register with the aperture in and into locking engagement with the tube 10. It will be apparent that with this arrangement the collapsible pedestal or tripod is secured permanently to the vertical standard comprising the telescoping tubes.

The note sheet rack or support includes the middle vertical supporting plate 30; and a hinged member 31 is rigidly and permanently secured to the lower end of said plate. Said hinged member is disposed between the friction arms 32 of a bracket 33 which latter is secured permanently to the upper end of the uppermost tube 13. Said

bracket 33 with its arms is arranged to overhang the vertical standard comprising the telescoping tubes whereby the better to distribute the weight of a heavy book or the like more or less equally on both sides of the center of the supporting standard whereby to prevent said standard from becoming unduly overbalanced. Said arms 32 are adapted to engage the hinged member 31 with substantial friction whereby to retain the rack securely in any angular position to which it may be adjusted.

The rack includes the two L-shaped shelf-members 35 which are pivotally secured permanently by suitable means as the rivets 36 to said middle plate 30 on opposite sides of the hinged member 31. Bars 37 and 38 are pivotally connected permanently by suitable means as the pins 39 to the upper end of said plate 30 and on opposite sides of the vertical axis of said plate and preferably substantially in line with the pivotal connection of said shelf-members 35 with said plate 30.

Other bars 40 and 41 are pivotally connected permanently intermediate the ends thereof to intermediate portions of said bars 37 and 38 respectively. The lower ends of said bars 40 and 41 are pivotally connected permanently to the upper ends of links 42 and 43 respectively; and the lower ends of said links 42 and 43 are pivotally connected permanently to intermediate portions of said shelf members 35. Other and locking links 44 and 45 are pivotally connected permanently to the pivotal connections of bars 40 and 41, and links 42 and 43, respectively and said links 44 and 45 are pivotally connected together and are also connected permanently with said plate 30 and slidably disposed in a vertically arranged slot 46 therein. Preferably said links 42 and 44 and 43 and 45, are of equal length, which length preferably is substantially equal to the distance between the pivotal connection 36 of said shelf members 35 with said plate 30 and the pivotal connection of said links 42 and 43 with said shelf members 35 whereby a parallelogram is or may be formed.

With this arrangement, the various above described bars and links composing the rack may be moved outwardly or inwardly with respect to said plate 30 whereby to enlarge or contract the effective dimensions of the rack and in the various adjusted positions of said bars said shelf-members 35 may be substantially horizontally disposed. Said locking links 44 and 45, when arranged in substantially a horizontal line, serve to lock the other adjustable components of the rack in adjusted position. When the rack is collapsed the construction is such that said links 42 and 43 may be moved to a position within said shelf members 35 and in parallel relation therewith, in which position

said bars 40 and 41 may be substantially parallel to said plate 30 and may be disposed within the width thereof as illustrated in Fig. 4. As thus arranged, said shelf-members 35 may be moved upwardly about their pivotal connections 36 to enclose the various bars of the rack and in folded condition will occupy some such position as that illustrated in Fig. 7.

10 In the folded position of the rack, the various bars thereof are adapted to occupy only the lower portion of the compartment formed between the folded shelf-members 35.

The stand is ultimately compacted into 15 its final form by moving said folded rack in the direction of the arrow, Fig. 7, so that the collapsed tripod and standard is or may be received within the upper portion of the compartment formed by the folded shelf-members 35. As thus finally arranged, the 20 completely collapsed stand will be disposed as illustrated in Fig. 8.

It will be seen that, as arranged, all components of the stand are secured permanently together and the stand may be collapsed into an exceedingly small space.

The structure may be otherwise modified without departing from the spirit of the invention.

30 I claim:

1. A collapsible music rack having a vertical supporting plate, shelf-members disposed on opposite sides of and pivotally connected with said plate, bars disposed on opposite sides of and pivotally connected with the upper end of said plate and adapted to swing over said plate above said shelf-members, links pivotally connected with said shelf-members intermediate the ends thereof, 40 bars pivotally connected with the upper ends of said links and the aforesaid bars, said links adapted to swing inwardly to a position approximately parallel with said shelf-members and with the outer pivotal ends 45 substantially in line with the pivotal connections between said shelf-members and plate, and pivotally-connected locking-links connecting said pivotally-connected links and bars, said locking-links having their 50 pivotally-connected ends slidably received in a vertical slot in said plate.

2. A collapsible music rack having a vertical supporting plate, shelf-members pivotally secured to and disposed on opposite

sides thereof at substantially right angles 55 thereto, a parallelogram on each side of said plate, each including said plate and a shelf-member and pivotally-connected links, said links having pivotal connection with said shelf-member and sliding connection with said plate, and articulated bars connected pivotally with said pivotally-connected links and said plate.

3. A collapsible music rack having a vertical supporting member, a horizontal shelf-member pivotally connected with said vertical supporting member, upper and lower, 60 pivotally-connected, links, the lower link pivoted directly to said horizontal shelf-member, and a link pivotally connected at 70 one end with said upper and lower links at the pivotal connection therebetween and said last link having its other end pivotally and also vertically slidably connected with 75 said vertical supporting member, the pivotal interconnection between said links arranged to lie approximately coincident with the pivotal connection of said shelf and vertical supporting members when the rack is collapsed, and said links constructed and arranged to lie within the boundaries of said 80 vertical and horizontal members when the rack is collapsed.

4. A collapsible music rack having a vertical supporting member formed with a vertical slot therein intermediate its ends, a horizontal shelf-member pivoted to said vertical supporting member below said slot, 85 pivotally-connected links of substantially equal length, one pivoted at its free end to 90 said horizontal shelf member and the other having its free end pivotally received in the slot in said vertical supporting member, said links and said shelf and supporting members arranged to form substantially a parallelogram when the rack is fully extended, and two other pivotally-connected links, one 95 having its free end pivoted to said vertical supporting member above the slot therein, and the other having its free end pivoted to the aforesaid links at the pivotal connection therebetween, and said links constructed and arranged to lie substantially within 100 the boundaries of said shelf and vertical members when the stand is collapsed.

In testimony whereof, I have signed my name to this specification.

FORTUNATO SORDILLO.
